(57) **CLAIM**

The ornamental design for a sports training device as shown and described.

DESCRIPTION

FIG. 1 is an elevational perspective view of the sports training device, showing the new design; the invention's outer surface/circumference is shown to be substantially transparent, despite being approximately twice the thickness of a common soccer ball.

FIG. 2 is a perspective view thereof;

FIG. 3 is a top view thereof;

FIG. 4 is a bottom view thereof;

FIG. 5 is a right-side view thereof;

FIG. 6 is a left-side view thereof;

FIG. 7 is a front view thereof; and,

FIG. 8 is a rear-backside view thereof.
